UNITED STATES PATENT OFFICE.

GUGLIELMO TREMOLADA, OF DETROIT, MICHIGAN, ASSIGNOR OF ONE-HALF TO
MICHAEL BARONI, OF WINNIPEG, MANITOBA, CANADA.

REINFORCED SPRING.

1,392,540.

Specification of Letters Patent.

Patented Oct. 4, 1921.

Application filed November 14, 1917. Serial No. 202,026.

To all whom it may concern:

Be it known that I, GUGLIELMO TREMOLADA, a subject of the King of Italy, residing at the city of Detroit, in the State of Michigan, have invented certain new and useful Improvements in Reinforced Springs, of which the following is a specification.

This invention relates to the production of an article of manufacture which is of resilient quality in cross section but which is nonresilient in longitudinal direction, the said article being capable of a variety of applications, a number of which with their objects, will be found first fully described in the following specification and the means by which the said objects are attained then more particularly pointed out in the appended claims, reference also being had to the accompanying drawings in which similar characters of reference indicate similar parts throughout the different views, and in which—

Figure 1 shows a solid core having a spring closely wound therearound to form a member such as is described in the preamble.

Fig. 2 shows a similar core member having a spring of open winding coiled therearound, the spring being shown partly in section.

Fig. 3 is a sectional end view of the subject matter of the invention having a three strand core.

Fig. 4 shows a plurality of the reinforced springs interwoven in the manner of a fabric.

Fig. 5 is a section taken on the plane of the line 5—5 in Fig. 4.

Fig. 6 shows layers of the springs superposed on each other with a sheet of fabric interposed between the layers, the whole being vulcanized together.

Fig. 7 is a section on the line 7—7 in Fig. 6.

Fig. 8 shows a plurality of the spring members woven with a warp of ordinary cord.

Fig. 9 is a section taken on the line 9—9 in Fig. 8.

Fig. 10 is a cross section of an automobile tire having the springs incorporated therein, the said section being taken on the plane of the line 10—10 in Fig. 11.

Fig. 11 is a section of the tire taken on the line 11—11 in Fig. 10.

Fig. 12 shows a plurality of the spring members superposed in parallel and with a fabric interposed between.

Fig. 13 shows a plurality of the spring members superposed but without the dividing fabric.

As is clearly shown in the drawings, the article consists of a core member 1 preferably of vegetable fiber, which may be single, solid and flexible as shown most clearly in Figs. 1 and 2, or it may be formed from a plurality of strands 2, twisted together in the manner of a rope as is shown in Fig. 3. A spring 3 is helically wound tightly around the core 1, the convolutions of the spring being preferably contacting as is shown in Fig. 1, though they may in certain cases be separated as is shown in Fig. 2, and the ends of the core 1 may of course extend beyond the ends of the spring to any desired extent. The member so built up and indicated as a whole by the letter A, is flexible in all directions and resiliently responsive in cross dimension, and its diameter may vary from that of a very fine cord upwardly, this being governed by its future application.

In Figs. 4 and 5 a plurality of the members A are shown woven together to form a fabric, the said members in this instance forming both the warp and woof of the structure. Experiments with a fabric formed in this manner have shown that it will successfully resist a revolver bullet fired at a distance of thirty feet, thus establishing a value for the device in modern warfare.

In Figs. 6 and 7 the members A are superposed in layers at right angles to each other, a piece of fabric 5 being interposed between the layers and the whole vulcanized together to form a resilient waterproof fabric suitable for a number of purposes which will readily occur to persons skilled in the art to which such things pertain.

Figs. 8 and 9 show the spring members A woven with a warp 6 of ordinary type, this construction also lending itself to vulcanizing purposes. Figs. 12 and 13 are also examples of possible combinations for vulcanizing purposes.

In Figs. 10 and 11, 7 indicates the tread portion of an automobile tire cover and 8 the sides of the same. The spring members A it will be noted, are preferably placed

to follow the lateral curve of the tread and the ends 4 of the cores may extend the full depth of the sides as is shown at 9, and they may further be interwoven with the 5 tire fabric as is indicated at 10. The members A are preferably placed in the tire in two or more tiers or layers, so that they not only add to the shock absorbing qualities of the tire, but also serve, by their proximity to each other and the fact that the joints 10 between the members of each row are covered by those of the succeeding row or rows, to prevent puncturing.

While a variety of applications of the 15 article have been shown in the drawings, no attempt has been made to exhaust such instances, nor to show the variety of ways in which the article might be made; it is of course preferable that the spring should 20 be made from finely tempered steel, but material is not an essential feature of the device and other metals might be substituted. When the spring is made from steel the most outstanding usefulness for the 25 article would appear to be in connection with

the manufacture of automobile tires and bullet proof clothing, and the fact that more than one spring could be coiled on the same core is of course obvious.

Having thus fully described my said invention, what I claim is:—

1. A vehicle tire providing a tread portion having a plurality of resilient members incorporated thereinto each comprising a core of flexible nonelastic material having 35 its ends interwoven with the fabric of the tire and a wire spring coiled around its medial portion.

2. A vehicle tire providing a tread portion having a plurality of resilient members 40 vulcanized thereinto in layers, the members of each layer breaking the joints between those of the next layer, and each of the said members comprising a flexible nonelastic core having its ends forming part of the 45 tire fabric and a wire spring coiled tightly around its medial portion.

In testimony whereof I affix my signature.

GUGLIELMO TREMOLADA.
